NATHAN W. SCHIRESON, OF LOS ANGELES, CALIFORNIA, ASSIGNOR TO SCHIRESON BROS.,
OF LOS ANGELES, CALIFORNIA, A COPARTNERSHIP COMPOSED OF NATHAN W.
SCHIRESON AND JACOB SCHIRESON

STRINGED MUSICAL INSTRUMENT

Application filed October 29, 1931. Serial No. 571,781.

The invention relates to improvements in stringed musical instruments.

An object of the invention is to provide a novel, simple and durable construction of 5 stringed instrument, such as a guitar or the like, in which the sounds or notes produced by the instrument are amplified without distortion. In the conventional stringed instrument, such as a guitar, there is a hollow body 10 serving as the sound box of the instrument. The vibrations of the strings are amplified by this hollow body to a certain extent which ordinarily is regarded as adequate. However, in the present construction, although 15 there is a hollow body present similar to any conventional hollow body, there is also an amplifying construction associated therewith which will amplify the sounds produced by the vibrating strings to a greater extent than 20 that which is capable of being accomplished by the hollow body alone.

Another object of the invention is to provide an improved stringed instrument having a special sounding board which is separate 25 from the body of the instrument.

A further object of the invention is to provide a construction having a sounding board beneath which there is a member which provides a concavity open toward the sounding 30 board. This member presents surfaces which are spherical as distinguished from conical. By having the surfaces so formed, sound waves striking the surfaces will be reflected and at the same time dispersed, thus increasing 35 the effective volume of sound which can be heard.

With the foregoing and other objects in view, which will be made manifest in the following detailed description, and specifically pointed out in the appended claims, reference is had to the accompanying drawings for an illustrative embodiment of the invention, wherein:

Fig. 1 is a top plan view of the improved 45 stringed instrument.

Fig. 2 is a sectional view taken substantially on the line 2-2 of Figure 1.

Fig. 3 is a top plan view of the sounding board.

Fig. 4 is a top plan view of the cover.

Fig. 5 is a top plan view of the instrument, the cover and strings being shown as having been removed to illustrate internal construction.

Referring to the accompanying drawings, 55 wherein similar reference characters designate similar parts throughout, I have illustrated the invention as having been embodied upon a guitar although the invention may be incorporated in any other form of stringed musical instrument. The guitar illustrated has a bottom 10, side walls 11, and a top 12, within which there is formed a large circular opening 13. A circular ring 14 is mounted on the under side of the top 12 around aperture 65 13 and provides a shoulder 15. This ring may be supported or reinforced as by posts or columns 16. The shoulder 15 provides a seat for the edges of a sheet metal concavo-convex member 18. Near the edges of this concavo-convex member 18 there is formed an annular bead 19 serving to stiffen this member adjacent its edges and within the bead there is a short annular flat portion 20. Within the short annular flat portion the sheet metal 70 member presents a large concave area on its upper side and a convex area on its lower side. The curvature or formation of these areas are such that they substantially conform to a portion of a true sphere, although 75 there may be a slight departure from a true sphere under certain circumstances. Above the sheet metal member there is positioned a circular sounding board 23 having apertures 24 formed therein. This sounding board may 80 be formed of any one of a number of different materials but I prefer to employ spruce wood which has been suitably seasoned. This sounding board carries a ring 25 adjacent its edges which rests upon the annular flat surface 20 of the sheet metal member 18. The sounding board is also stiffened and reinforced by transversely extending cleats 26 and 27 secured to the under side of the sounding board. The sheet metal of member 18 is 85

very thin, being preferably about 32 gauge aluminum. While the curvature of the large central area and the presence of the bead 19 tend to stiffen this member, it nevertheless has some resiliency. Consequently it does not 90 100

form an absolutely rigid support for the sounding board 23 but may give slightly under the pressure placed on the sounding board. On top of the sounding board there is positioned a bridge 28 having string seats in the form of notches 29 for the reception of strings 30. Apertures 31 extend through the bridge beneath each string seat. The purpose of these apertures is to increase the resilience of the bridge slightly so that the bridge will not be a rigid solid body. Over the opening 13 there is positioned a cover plate 33 the central portion of which, indicated at 34, is flat. The sides 35 converge upwardly to points indicated at 36 where they are bent downwardly toward the flat central portion 34. In this manner the flat central portion 34 provides a relatively wide groove in the cover plate between the upwardly convergent sides. In the bottom of this groove there is formed a rectangular opening 37 for the reception of the bridge 28. This opening is formed by striking out a portion of the body of the cover plate to form a bridging plate 38 over the opening which is disposed above the bridge 28 and serves to protect it. The cover plate, which is perforated, may be fastened to the top 12 of the body as by suitable screws 39.

When a string 30 has been picked or has been struck to cause it to vibrate, these vibrations are transmitted by the bridge to the sounding board 23, which is more or less resiliently mounted at its edges on the concavo-convex sheet metal member 18 near the edges of the sheet metal member. The sounding board serves to amplify these vibrations and to vibrate the body of air between the sounding board and the sheet metal member 18.

Some of the sound strikes the concave surface of the sheet metal member so that this sheet metal member acts as a sound reflector. The sound reflector being spherical in shape reflects sound waves in accordance with well established physical laws wherein the angle of incidence is equal to the angle of reflection. The shape of the reflector, therefore, in reflecting the sound causes a dispersion of sound to take place so that a note produced by the instrument may be heard clearly in virtually any direction above the instrument. Although I am not prepared to set forth any definite theory as to exactly what takes place, I do not believe that the sole function of the sheet metal member 18 is a sound reflector. This member is supported at its edges only and as the sounding board rests on the member inwardly of its edges, the central portion of the member 18 is likewise free to vibrate.

It is thought that this member also vibrates in accordance with vibrations of the sounding board so that it has the function not only of reflecting sound but also as an auxiliary sounding board. Such being the case, the body of air within the hollow body but out-

side of the sheet metal member 18 will be vibrated thereby, thus amplifying the sound. This sound is not confined within the body but may escape through suitable apertures 40 formed in the top 12. The spherical shape 70 not only has the advantage of reflecting the sound and dispersing it as distinguished from a conical structure which usually has the tendency to confine the sound but it also materially strengthens the sheet metal. I am 75 able to use a very thin sheet aluminum so that the weight or mass of the member 18 is very small, rendering it capable of being easily and quickly influenced by the vibrations imparted to it. From actual experiment I find 80 that a note produced by striking or picking a string of the instrument can be greatly amplified without distortion. The volume of the note is greatly increased over that of the conventional guitar or equivalent stringed instrument yet the note will be clear and melodious without any harsh or disagreeable distortion. The bridging plate 38 on the cover 85 may serve as a hand rest for the hand employed in picking or striking the strings 30 and prevents the hand of the player from coming in contact with the bridge. In this manner the bridge, sounding board and sheet metal member are effectively protected.

From the above described construction it 90 will be appreciated that a relatively simple, durable amplifying construction has been provided for stringed instruments, which is of simple and durable construction and which is effectively protected.

Various changes may be made in the details of construction without departing from the spirit or scope of the invention as defined by the appended claims.

I claim:

1. A stringed instrument having a hollow body with an opening in its top, an upwardly concave member supported within the body, a bridge for supporting the strings of the instrument, and a sounding board supported at its edges upon said member upon which the bridge is mounted.

2. A stringed instrument having a hollow body with an opening in its top, an upwardly concave member supported within the body, a bridge for supporting the strings of the instrument, and an apertured sounding board supported at its edges upon said member on which the bridge is mounted.

3. A stringed instrument having a hollow body with an opening in its top, an upwardly concave member supported within the body, a bridge for supporting the strings of the instrument, and a sounding board supported at its edges upon said member adjacent the 120 edges of said member on which the bridge is mounted.

4. A stringed instrument having a hollow body with an opening in its top, an upwardly concave member supported within the 130

body, a bridge for supporting the strings of the instrument, and an apertured sounding board supported at its edges upon said member adjacent the edges thereof, said sounding board constituting a support for the bridge.

5. A stringed instrument having a hollow body with an opening in its top, a sheet metal concavo-convex member supported at its 10 edges within the body with the concave side uppermost, a bridge for supporting strings of the instrument, and a sounding board resting at its edges upon said member upon which the bridge is mounted.

15. 6. A stringed instrument having a hollow body with an opening in its top, a sheet metal concavo-convex member supported at its edges within the body with the concave side uppermost, a bridge for supporting strings 20 of the instrument, and an apertured sounding board resting at its edges adjacent the edges of said member upon which the bridge is mounted.

7. A stringed instrument having a hollow 25 body with an opening in its top, a sheet metal concavo-convex member supported at its edges within the body with the concave side uppermost, a bridge for supporting strings of the instrument, and means for supporting 30 the bridge upon said member, said member presenting surfaces which substantially conform to a portion of a true sphere.

8. A stringed instrument having a hollow 35 body with an opening in its top, a sheet metal concavo-convex member supported at its edges within the body with the concave side uppermost, a bridge for supporting strings of the instrument, and an apertured sounding board resting at its edges adjacent the edges 40 of said member upon which the bridge is mounted, said member presenting surfaces which substantially conform to a portion of a true sphere.

In testimony whereof I have signed my 45 name to this specification.

NATHAN W. SCHIRESON.
